UNITED STATES PATENT OFFICE.

DENNIS BRENNAN, JOHN R. WIRLEY, AND EVERETT GOLDTHWAIT, OF ELKHART, INDIANA.

DEVICE FOR BENDING ANGLE-BARS.

SPECIFICATION forming part of Letters Patent No. 608,829, dated August 9, 1898.

Application filed March 12, 1898. Serial No. 673,623. (No model.)

To all whom it may concern:

Be it known that we, DENNIS BRENNAN, JOHN R. WIRLEY, and EVERETT GOLDTHWAIT, citizens of the United States, residing at Elkhart, Indiana, have invented certain new and useful Improvements in Devices for Bending Angle-Bars, of which the following is a specification.

Our present invention relates to an improved device for straightening the angle plates or bars of rail-joints; and the object of the invention is to provide a simple and effective but light and easily-portable device by means of which the angle-bars may be straightened without regard to the nature of the bend and at the point where they are used without necessitating their being carried to a shop or like repair-house.

The invention is illustrated in the accompanying drawings, in which—

Figure 1 is a plan view of the device as used in straightening the plate, showing a sufficient portion of a railroad-rail to illustrate the invention as applied to the bar in the position shown in Fig. 4. Fig. 2 is a side elevation of the device, showing the rail in section. Figs. 3, 4, and 5 are views showing the fish-plate in the various positions assumed according to the way the fish-plate may have become bent or distorted. Fig. 6 is a detail view.

In the drawings the rail is designated at 1 and the clamp or press by means of which the necessary pressure is secured at 2. This consists of a metal bar having at one end a hooked portion 2^a, adapted to hook over the lower inside flange 3 of the rail and abut against the web, as clearly shown in Fig. 2. The opposite end of the bar is provided with an arm 12, having a threaded opening through which passes the screw 11, having preferably an enlarged head 11^a, provided with holes 11^b for the reception of a suitable handle for turning. While this form of power is preferable, we do not desire to limit ourselves to the screw for obtaining power.

The angle plate or bar to be straightened is shown at 14, and in order to hold it spaced a suitable distance from the rail to permit the application of pressure from the screw to straighten it bearing-blocks 5, 6, and 7 are

employed. Of these the blocks 6 and 7 are counterparts of each other and are located one at each end of a connecting-rod 8, while the other block 5 is located approximately centrally thereof. All of these blocks may be made longitudinally adjustable on the rod by means of screw-threads or in any other desirable manner. The rear faces of the blocks are shaped to rest firmly against the outer face of the rail and upon the lower flange 4, while the outer or front faces are shaped to receive and support the angle-bars in a number of positions, according to the bent condition of the angle-plate to be straightened. 65

The forward end of the screw 11 is rounded and adapted to bear against a rounded socket in a bearing-block 10. This bearing-block has three faces differently shaped to fit the faces of the angle-bar in as many positions 70 and has three rounded sockets in its three remaining sides for the end of the screw, as before stated.

Referring more particularly to Fig. 2, in which the parts are shown in position for bending the angle-plate, it will be observed that the bearing-blocks 6 and 7 have notched or recessed portions *a* and slightly-inclined forward edges *b*, the former offering seats for the head or upper edge *a'* of the angle-bar, 80 while the latter serves to support the lower edge *b'*. The central block 5 rises only to a fraction of the height of the blocks 6 and 7, as clearly shown in dotted lines, and does not extend out so far from the rail, so that 85 when pressure is applied to the central portion of the under side of the angle-bar by screw 11 and pressure-block 10 the base-flange of the angle-plate is free to be forced inwardly. The upper edge, however, of the 90 bearing-block 5 is inclined, and as pressure is applied to the plate, forcing the portion *a'* into the seats *a* and bending it in at the center, as before described, the inclined surface of the block 5 tends to lift the central portion 95 of the edge *a* slightly.

In Fig. 3 we have shown the angle-bar in another position, adapted to be straightened to remove a bend of a different shape. In this it will be seen that the base of the angle bar or plate rests against seats or bearing-faces *c* and *c'*, the central block 5 not being

necessary in this position and not contacting with the surface of the angle-bar. It will also be observed that the block 10 has been shifted to bring its corresponding side in contact with the upper edge of the angle-bar.

In Fig. 4 the angle-plate is shown in still another position, in which it will be observed that the upper edge of the angle-bar, which is here shown upside down, rests against shoulders *d* of the blocks 6 and 7.

For holding the angle-plate in still another position we find it desirable to provide additional bearing-blocks 13, having faces *e*, adapted to abut against the inner face angle-plate in the position shown in Fig. 5. These may or may not be connected, as desired, and while we prefer to place them against the blocks 6 and 7 we do not limit ourselves in this respect.

From the foregoing description it will be readily apparent that a portable and extremely advantageous device is provided. By reason of thus utilizing the rail as a part of the device when in operation the number of parts to be carried around are greatly reduced and the weight decreased to a degree which renders it possible for the workman to carry it easily from place to place. The angle-bars can thus be straightened at the point of use without the necessity of sending them to the repair-shops.

It will be understood that while we have illustrated and described the invention in connection with the ordinary rail and fish-plate, we do not limit ourselves to the particular form of the rail and fish-plate, as the invention is equally adapted to rails and fish-plates of any form.

Having thus described our invention, what we claim is—

1. A device for bending or straightening railroad angle-plates comprising the clamp adapted to engage the rail, bearing-blocks adapted to abut against the rail and having bearing-faces to sustain the angle-plates, and means for applying pressure to the unsustained portion of said angle-plates, substantially as described.

2. A device for bending or straightening angle bars or plates comprising the clamp adapted to engage the rail, the connected bearing-blocks adapted to rest against the rail and having surfaces designed to sustain the angle-plate, and means for applying pressure to the unsustained portion of said angle-plate, substantially as described.

3. A device for straightening or bending angle-plates comprising the clamp adapted to engage the rail, the bearing-blocks adapted to abut against the rail and having a plurality of sustaining-surfaces adapted to sustain the angle-plate in a plurality of positions, and means for applying pressure to the unsustained portion of said angle-plate, substantially as described.

4. A device for straightening or bending angle-plates comprising the clamp adapted to engage the rail, the central and end blocks adapted to abut against the rail, bearing-surfaces on said end blocks adapted to sustain the ends of the angle-plates, an incline on said central block designed to contact with the under edge or face of the plate being straightened, and means for applying pressure to the central portion of the angle-plate, substantially as described.

5. A device for straightening or bending angle-plates comprising a clamp adapted to engage the rail, bearing-blocks adapted to abut against the rail and having a plurality of faces designed to sustain the angle-plate in a plurality of positions, a pressure-screw carried by said clamp, and a pressure-block adapted to be interposed between the screw and angle-plate and having also a plurality of bearing-surfaces conforming in shape to the various positions of the angle-plate, substantially as described.

In testimony whereof we affix our signatures in presence of two witnesses.

DENNIS BRENNAN.

JOHN R. WIRLEY.

EVERETT GOLDTHWAIT.
